WINDMILL

Mendel Shenk, Brooklyn, N. Y.

Application October 16, 1933, Serial No. 693,701

10 Claims. (Cl. 170—23)

This application is in the large part a substitute for the abandoned application, of March 24, 1931, Serial Number 524,988.

5 My invention relates to windmills of the rotary type.

The main object of my invention is to provide a windmill, that is capable of developing considerable more power, than the power developed by existing windmills.

10 Another object of my invention is to provide towers utilized for holding a connection or span, and the connecting means between the towers arranged to hold the upper bearing of a vertical shaft.

15 A further object of my invention is to provide a vertically arranged shaft carrying a framework of multangular formation, adapted to pivot a multiple of independent vanes, and means for automatically maintaining the vanes in certain angular positions for the rotation of the mill.

20 A still further object of my invention is to provide a windmill with vanes so pivoted, that they will position themselves quickly, and bring to a minimum counter-balancing of all kinds.

25 One feature of my invention consists in a windmill with a vertically driven shaft carrying a plurality of concentrically arranged, vertically pivoted vanes, and a plurality of superimposed horizontally pivoted and axially arranged vanes.

30 Another feature of my invention consists in the arrangement of the vanes pivoted in spaced relation to each other, in such a manner as to enable the vanes to utilize the full energy of the wind.

One unique feature of my invention consists 35 in the provision of a windmill having a vertically driven rotor, that is suitably connected to shafting adapted to drive mechanisms heavier, than that of the existing windmills.

One of the advantages of my invention consists 40 in the unique arrangement of the framework of the rotor, and the arrangement of the vanes pivoted thereon.

Another advantage of my invention consists in the arrangement and means utilized for automatically controlling the position of the vertically pivoted vanes.

45 Still another advantage of my invention consists in the means utilized for holding the framework, tie rods or wires, securely, and their connections to the rotating shaft.

50 One of the most important advantages of my invention consists in providing a windmill having a vertically driven shaft with a unique form of stopping means.

55 I attain these objects preferably by the means

illustrated in the accompanying drawings, and described hereinafter, wherein similar numerals refer to like parts throughout the several views, and in some figures only one or two of similar parts are numbered, in which:

5

Figure 1 is an elevation of the whole structure of the windmill, and shows the different positions of the vanes.

Figure 2 is a plan of the whole structure of the windmill, and shows the different positions of all 10 the vanes.

Figure 3, a plan view of Figure 4, is a detail illustrating the means of connecting the spokes and the outer supporting wires with the framing or hoop, and is the basis for some other 15 things, as set forth.

Figure 4 is a side elevation of Figure 3.

Figure 5 is a side elevation of Figures 6 and 7, fastened together, for holding the inner supporting wires, tie wires, spokes, the take-ups of the 20 means, utilized for controlling the vanes, and providing the tubular pivots for the bearings of the vanes.

Figure 6 is a plan of the bottom part of Figure 5, which is a means for holding the inner supporting 25 wires and all the other wires, which intersect at this point.

Figure 7 is a top view of the upper half fastened to that of Figure 6.

Figure 8 is a side elevation of the vertical vanes. 30

Figure 9 is a front elevational view of one of the vertical vanes.

Figure 10 is a diagrammatic view illustrating the means utilized for balancing the folded horizontal vanes 12 and the means for taking up the 35 slack of their vane controllers.

Figure 11 is a plan of a folded vane controller.

Figure 12 is a diagrammatic view of the stopping mechanism No. 1.

Figure 13 is a plan illustrating, how the connecting ropes are connected to the spool. 40

Figure 14 shows the connection of the horizontally pivoted vanes 14, with the spool of Figure 13.

Figure 15 is a modified diagrammatic view 45 illustrating the different positions of the vertical vanes during the operation of the device on a miniature size.

Figure 16 is a diagrammatic plan, illustrating the means utilized for taking up the slack of the 50 vane controllers during the movement of the vanes 16.

Figure 17 is an elevation of a shield for the pulley of Figure 16.

The windmill, as illustrated in Figures 1 and 2, 55

consists of a pair of structural towers A and A¹, having a cross framework or bridge B with a safe passageway near the top, and a building C between the towers.

5 The bridge B carries a system of rollers 1, into which the upper end of the rotatable shaft E is fitted, and the lower end of the shaft passing through an opening in the top of the building C, is fitted into a floating bearing 2.

10 Upon this shaft, preferably of a tubular formation, are arranged a plurality of discs 3, adapted to hold a plurality of wires or spokes 4 of sufficient strength that are connected to a plurality of connectors 5, as shown detailed in 15 the enlarged Figures 3 and 4, which in their turn connect a plurality of tubular elements 6, shown in Figure 2, forming a multangular hoop of the rotor D.

Said wires or spokes 4 are arranged in pairs. 20 One end of each wire is fastened to the opposite sides of the periphery of the disc 3, and the other ends of both the wires are fastened to one connector 5, thus giving this frame the stability of a wheel, and allowing, besides, a considerable increase of its diameter. (Figure 2.)

Such multangular frames are arranged horizontally, and are five in number, shown in Figure 1, one above the other; but they can be more or less, if desired.

30 As this number of multangular frames makes the shaft E unusually long, and this shaft cannot be made too thick and heavy, therefore, at both ends of the shaft E additional discs 7 and 7¹ are set up, which are connected with strong stay wires 8 and 8¹ to the connectors 5 of the outer two multangular frames, at the top and bottom of the rotor D.

These connectors in their turn are interconnected with the aligned connectors 5 of all the 40 inner multangular frames, by vertical reinforcing or supporting wires 9 of sufficient strength, thus securing the shaft E against dangerous vibrations, which may result in its bending or even breaking, and at the same time it protects also the frames of the rotor against dangerous vibrations, especially during a storm, which may twist and even break parts of the rotor structure.

Additional stay wires may connect the connectors 5 and the discs 3 higher up if desired.

50 Within these multangular frames, the tie wires 18 are connected together to the carrier spokes or wires 4, by means of connectors 11, shown in Figures 5 to 7 inclusive, hereinafter referred to.

Another set of vertical supporting wires, indicated by the dot-and-dash lines 10 of Figure 1, join the stay wires 8 and 8¹ and all the inner connectors 11 of all the other multangular frames, which they meet on their way.

However, the number of these inner vertical supporting wires 10 is just half of the number of the outer vertical supporting wires 9.

These rods or wires, tightened in a manner to be described hereinafter, make this framework of the rotor D strong and solid.

65 The upper portion of this rotor-structure carries a series of outer double vanes 12, 12a, 12¹ and 12a¹, and inner double vanes 13, 13a, 13¹ and 13a¹.

The next lower portion of the rotor-structure carries a series of outer vanes 14 and 14¹, and inner vanes 15 and 15¹, consisting of single vanes only.

All of these vanes are pivoted horizontally on, or about, every other spoke 4 and its extension 75 4¹. These spokes are carrier spokes. The re-

mainder of the rotor-structure carries a series of outer vanes 16, 16¹, and inner vanes 17 and 17¹, of still another type, (see Figures 8 and 9), which are pivoted vertically on the pivotal parts of the connectors 5 and 11, respectively, see Figures 1 5 to 5.

As shown in Figure 2, the number of the inner vanes is just half the number of the outer vanes. In case a third set of inner vanes is desired, then their number must be half of the vanes of the 10 second set. By this arrangement the vanes, by a sufficient distance between each other, receive the highest effect of the windpower.

The vane controller 19 keeps the vane in the desired angular positions, and consists preferably 15 of two or more linked wires, or of other metallic links, one end of which is connected with the vane, and the other end is connected with the connector, 5 or 11, of the following angle of the same ring-formation, as shown in Figure 2. 20

The bottom end of the vertical rotor shaft E carries a bevelled gear 20, that is connected with a system of gears and a stopping device.

The vanes of all types are not pivoted end-wise, as in other constructions, but the first type 25 is pivoted in or near the middle, and the other two types are pivoted about one quarter or one third the distance from one edge, and three-quarters, or two-thirds from the opposite edge.

This arrangement enables the vanes to change 30 their position much quicker, takes away some of the strain of the vane-controller 19, allows the vane-controller to be shorter, and lessens the shock at the connection-points of the vane-controller.

From the connectors 5 of the upper two multangular frames, a tubular piece 4¹ is extended outwardly in the line of the carrier spoke 4. The outer end of each extension 4¹ is tied by wires 4¹¹ to the nearest connectors 5, right and left 40 on the same frame, see Figure 2.

For a better stability, the outer end of the extension 4¹ can also be tied to the connector 5 of the above frame. It is not indicated here in order to avoid crowding.

The vanes 12, 13, 14 and 15, are pivoted with one end to the carrier-spoke 4 and with the other end to the corresponding extension 4¹.

This arrangement makes the size of the multangular hoops smaller, and brings the point of 50 support of the vane-controller, the opposite connector 5, against the middle of the foregoing vane, what is advantageous in many respects, as seen in Figures 1 and 2.

The vertically pivoted vanes do not need any 55 extensions beyond the multangular hoops.

The upper vanes 12 and 13 consist of two halves each, hinged directly or indirectly, to a spoke 4 and to its extension 4¹, and can easily be folded and unfolded, (this will be explained with Figure 10). Each free end of these halves is provided with a vane-controller 19 or two of them, the other ends of which are fastened to the (dotted) ears 5¹ of one connector 5 or 11, so that both halves cannot move beyond a desired distance.

The vane-controllers 19 of all the other vanes are fastened to the longer ends of the vanes, and the other ends of the vane-controllers are fastened to their respective connectors.

No matter from which side the wind comes, it unfolds automatically the vanes 12 and 13, pushes away the longer halves of the vanes 14, 15, 16, and 17, thus bringing them in a resisting, and therefore, operative position on one side, and in an 75

inoperative position on the other side of the rotor D, which makes the rotor revolve always in one direction, as is seen from the Figures 1 and 2, in accordance with the arrows at the foot of Figure 2.

The enlarged outer connector 5, illustrated in the two views of Figures 3 and 4, is preferably comprised of an inner portion 5, that is threaded at both ends to engage the tubings 6, and has two holes, to receive the spokes 4 near the central part.

To each side of this central portion 5, are riveted or screwed through the holes 21, two portions 22 and 22¹. The connectors of the outer frames 15 of the rotor D have only one portion 22.

The part 22 is provided with a boss 23, in the centre of which the supporting wire 9 is fixed, either by screwing or in any other suitable manner.

Upon the boss 23, is loosely journaled or pivoted the vane-controller 19a, or the take-up 24, to the outer end of which the vane-controller 19 is secured, see Figures 11 and 25.

Part 26 is the bearing of the third type vane 16; between 24 and 26 is tightly set up or screwed a nut 25, but this nut does not press on the part 24, nor on the part 26, and allows them a free movement around the boss 23.

The portion 22¹ has the same parts, as portion 30 22, but in a reversed order, and is destined for another vane 16, and another vane-controller 19 or 19a to be used on the other side of the same multangular frame of the rotor D.

The inner connector 11, shown in Figures 5, 6 35 and 7, is preferably comprised of a can-like box 11, to which the upper portion 11¹ is screwed through the holes 21. Both parts are provided with bosses 23, that centrally carry the supporting wires 10 secured, either in the way shown, or in 40 any other suitable manner.

Upon these bosses 23, the vane-controllers 19a or the take-ups of the vane-controllers 24 are loosely journaled or pivoted; over them the nuts 25 are fixed, and over the nuts the vane-bearings 45 26 are pivoted. All of the parts on the other side are alike, but set up in a reversed order, substantially as shown in Figure 4.

The part 11, (Figure 6), has a can-like form with a bottom beneath. The outside of the bottom has a boss 23, and in the centre is a hole for the end of the supporting wire 10. The wall of this part 11 is thicker in four places 27.

Through these thicker places are holes to receive the spoke-ends 4 and the tie-wires 18, which all 55 are secured and tightened by nuts like 28 within the part 11.

And the part 11¹ (Figure 7) is screwed on the top of part 11, through the holes 21, and lying snugly upon the nuts, secures them in place.

For those multangular frames (Figures 1 and 2), which are adapted for the vanes of the first two types 12 and 14, the connectors 5 and 11 are somewhat simplified, but remain substantially the same, as the connectors just described.

Figures 8 and 9 illustrate the form of construction of the vanes 16 and 17, which consist of a metal frame of tubular or L formation, covered with a one-piece suitable material. The vane is provided with bearings 26, through which the 65 supporting wire 9 or 10 passes.

The vane is further provided with ribs 29, bosses 30 and suitable bracing wires 31 on both sides lengthwise and diagonally to the vane frame, so that the vane may be stiffened to withstand 70 the highest wind pressure.

The vanes like 12 and 14 may differ in size, shape and in other minor particulars, but are constructed in the same way, as the vanes 16 and 17.

Figure 10 illustrates a means for balancing the horizontal vanes 12 and 13, repeated in two superimposed sets. These vanes are made of two parts 12 and 12a; the part 12 is provided with a bell-crank 32, that has the upper arm connected by means of a rope or chain 33 to a pulley 34, attached to the structure 4a, which is built at the top of the rotor D, (Figure 1). This rope or chain passes over another pulley 34¹, and the end is connected to the upper arm of another bell-crank 32¹, which is connected to the lower half-vane 12a.

The other arm of this bellcrank 32¹ is connected by the wire 33¹ to the upper arm of the bellcrank 32², attached to the end of the half-vane 12a, of the second set, and the other arm of this bellcrank may be connected further down to another set of vanes, and so on.

The lower arm of the bellcrank 32 is connected by a wire 35 to the upper arm of the bellcrank 32¹, that is attached to the end of the half-vane 12, of the second set, and the lower arm of the bellcrank 32¹ is connected with a wire 35¹, that can be connected further to another set of vanes, or is connected with a rope 38, which is fastened to the tubular element 39, that is adapted to bring these vanes in an inoperative position, (see Figures 12 and 13).

Figure 11 is a plan of a folded vane-controller, preferably adapted for the vanes 16 and 17, but could be used also for the other vanes, wherein 35 19a is a frame, through which a plunger 36 is running.

This plunger has a head with a prolongation 37 on one side, slideable upon the frame 19a, one side of which is provided with a ring 23¹, pivoted upon the boss 23 of the connector 5 or 11, and the hole of the plunger-head 36¹ is journaled to a corner of the vane 16 or 17, see Figures 4 and 5.

The frame 19a may be covered in any suitable manner to protect it against exposure, or wholly consist of a tubing.

Figure 12 is a side view, and Figure 13 is a plan, which both illustrate the means used to stop the movement of the rotor D for repairs.

The rotor shaft E, near its passage through the building top C, carries between two fixed rings "e" a spool 39, rotatable around the shaft.

The spool 39 has a slanted and wider rim above, and a straight and smaller rim beneath, which has a projection 39¹ below.

The ropes 38, one end of which are connected with the vanes, pass through suitable pulleys and are tied to the spool 39.

To the top of the building C at a point 40, is pivoted a lever 41, bent at 42 toward the spool 39.

When the lever 41 is pulled by its handle 43 to the left, the upper end engages the projection 39¹ and stops the spool from movement; but the shaft E, continuing to rotate, coils around the spool the ropes 38, which pull with their other ends the vanes, bringing them in an inoperative position, and the rotor stops, see Figures 10 and 14.

When the lever handle 43 is pulled the other way, the upper part of the lever releases the spool, and the wind gradually brings the vanes in the operative position again.

Figure 14, diagrammatically illustrates the connection of the vanes of the second type 14 and 15, with the spool 39, repeated in three su- 75

perimposed sets, wherein 6 are the tubular hoops of the rotor; 9 are the vertical supporting wires; 14 are the vanes pivoted just at the angle, where 6 and 9 coincide; 19 are the linked vane-controllers, which are tied with one end to the longer half of the vane, and with the other end tied to the opposite connector 5, which occupies the other corner of 6 and 9, not shown.

The longer halves of the vane 14, keeping all ways down, bring the vanes in a vertical position, and the vane-controller is then stretched. The wind pushes the vane together with the rotor D so far, that the vane is turned to the wind with its other side, and the wind brings the vane in 15 a horizontal position. (Figures 1 and 2).

The wire 44 connects the shorter ends of the aligned vanes, and the longer end of the bottom vane is connected with the rope 38, which goes through a system of pulleys, and is tied to the 20 spool 39, (see Figures 12 and 13), which by pulling these ropes, brings the vanes in a horizontal position, and the rotor stops.

The vanes 16 and 17 are stopped by bringing in any suitable way nine outer and four inner 25 vanes parallel to each other in one direction and the other vanes in the opposite direction.

The slack of the vane-controllers of the vanes of the first type 12 and 13 is taken in this way:

As these vanes consist of two halves (Figure 30 10), therefore, the upper vane-controller at the top of the rotor, linked at 19¹, is suspended by a wire to some part of the upper structure of the rotor; the upper vane-controller of the second set is connected with the lower vane-controller 35 of the first set by a rope or linked wires 19¹; the upper vane-controller of the third set is connected with the lower vane-controller of the second set, and so on. And the lower vane-controller of the last set can be left alone, as there 40 is nothing to come in contact with it. All of these connections and suspensions are shown by dotted lines in Figure 10.

Figure 15 is a modified diagrammatic view 45 illustrating the relative positions of the vanes, shown diagrammatically mounted on the tubing 31, pivoted by the pivot 31¹ at e¹, upon the handle E¹ of a miniature size. The spoke 4 and supporting wire 9 of Figure 1 consist here of one elbowed wire 4.

50 A part of the vane on two sides are bent towards each other, and serve as bearings 26. The cuts like 26¹ of such vanes, preventing the vanes to commit more than half a turn, serve as vane-controllers, and some thickening of the end of the wires 4 keeps the vane in place.

55 Figure 16 illustrates the means of taking away the slack of the vane-controllers of the third type vane 16, whereby vane 16 is pivoted upon the vertical supporting wire 9, which is connected with the tubular elements 6 of the multangular frames of the rotor, see Figures 1 and 2.

The vane-controllers 19, consisting of wires linked at 19¹, are connected with one end to the corners of the vane 16, and with the other end to the take-ups 24, pivoted to the supporting wire 9a.

60 The upper vane-controller 19 carries a pulley 67, and to the lower linking place 19¹ a wire 68 is connected, which goes up to the point 68¹, where it is connected with a rope or chain 68¹, turned over the pulley 67, and is tied to a weight 69, which slides upon the wire 68.

65 As long as the vane-controller 19 is stretched, the weight 69 is near the pulley 67, but when the 70 vane is in the position shown in Figure 25, the

weight 69 slides down, and brings both the vane-controllers 19 in the position shown in this figure, depriving them of a free swinging around.

Figure 17 represents a square bell-like cover 67¹, within which the pulley 67 of Figure 16 is 5 placed for protection against exposure.

Remarks and supplements

Where the power supply of one windmill is not sufficient, two mills or more may be built, and 10 because of their height they need not be very far apart.

One of the towers A is provided with a ladder, stairs or lift, enabling anybody to reach the bridge B for repairing, for greasing of the upper 15 bearing of the shaft E, and for other purposes. Figures 1 and 2 show two towers, but there can be three or four of them, if desired.

Both the towers are of triangular cross-formation, vertical toward each other and slanting on 20 the other sides, their tops are fastened to the ground by strong cables c. See Figures 1 and 2.

The bridge B is constructed of a system of cables and strong wires, with cross-cables "a" at 25 its bottom and other cables b suspending the middle of the bridge to the tops of the towers, in order to eliminate horizontal vibrations and to avoid a lowering of the middle-part of the bridge. The bridge B is provided with railings 30 on both sides for a safe passage, as seen in Figure 1.

The dotted lines 4a on the top of the rotor (Figure 1) is preferably constructed like the multangular frames, and is supported by forked tubings upon the upper regular multangular frame. 35

In case the vanes of the first two types are not used, this structure is not necessary at all.

The stay wires 8 and 8¹ do not align with the 40 spokes 4 (Figure 1), therefore, each inner connector 11 of the outer rotor frames is fastened to two stay wires by two links, a longer and a shorter one.

There is no necessity to use all the three types of vanes in any one rotor, and repeat them in 45 all the views here, as one or two types may be selected, and the rotor adapted accordingly.

When only the vanes 16 and 17 are used, the stay wires 8 and 8¹ and their nearest discs 3 may be omitted, but these spokes 4 attached to the 50 discs 7 and 7¹ at the same slant, as the stay wires 8 and 8¹. See Figure 1.

The slack is taken up in Figure 16 by the weight 69. This is not a necessity, for it can be done also with a spring.

As seen from Figure 25, the vanes of the third type 16 and 17 have two vane-controllers, one on the top, and one at the foot of the vane.

Having thus illustrated and described the preferred embodiment of my invention, I do not 60 wish to limit myself to the exact construction and arrangement of the parts shown, since it is evident, that modifications may be made therein, without departing from the spirit of the invention or scope of the claims.

65 What I claim, and wish to cover by Letters Patent is:

1. In a windmill of the character described, including a vertically arranged rotor carrying a plurality of radially arranged vertically pivoted vanes 70 each provided with top and bottom vane controllers, a pulley attached to each top vane-controller and a wire attached to each bottom vane-controller, said wire passing loosely through a weight, is connected to a flexible element, which 75

is turned over the said pulley and attached to said weight, thereby keeping the lower vane-controller loosely lifted and at the same time preventing both the vane-controllers from swinging around, when the vane changes its positions.

5 2. In a windmill of the character described, a rotor comprising: a vertical shaft; a plurality of superimposed hoops surrounding said shaft, each hoop consisting of straight tubular sections connected together by connectors; spaced discs on said shaft, one for each hoop; wires connecting each connector with two laterally spaced points on one of said discs, thereby forming spokes for said hoops; vertical supporting wires connecting 10 corresponding connectors on said hoops, wind vanes having bearing means pivotally engaging corresponding connectors of certain adjacent hoops, said bearing means being offset to one side of the plane of the vanes to accommodate said 15 vertical supporting wires; and a vane controller consisting of linked wires connecting a free edge of each of said vanes with an adjacent connector, whereby each of said vanes is free to align with the wind when on the side of the rotor which is advancing into the wind, but is restrained to a 20 transverse position to the wind by said vane controller when on the side of the rotor which is moving with the wind.

3. The structure set out in claim 2 further characterized in that said shaft is provided with additional discs, one above the uppermost hoop and one below the lowermost hoop, slanting connecting wires between the connectors of the uppermost hoop and the first mentioned additional disc and between connectors of the lowermost hoop and the second mentioned additional disc, whereby said rotor is braced against its own weight and against vibrations.

4. The structure set out in claim 2 further characterized in that the spokes of each of said hoops at joints intermediate their ends are provided with connectors, tie wires joining the last named connectors of each hoop and additional vertical wires connecting all these aligned connectors with said top and bottom slanting wires to thereby additionally brace said rotor, additional wind vanes to the number of substantially one-half of the number of first mentioned wind vanes pivotally secured to the last named connectors.

50 5. In a windmill of the character described, a rotor comprising: a vertical shaft; a plurality of superimposed hoops surrounding said shaft, each hoop consisting of straight tubular sections connected together by connectors; spaced discs on said shaft, one for each hoop; a spoke connecting each connector with one of said discs; outwardly radiating extensions attached to said hoop by said connectors, vertical supporting wires connecting corresponding connectors on said 55 hoops, wind vanes on said rotor, each horizontally pivoted at one of its ends to one of said spokes and at its other end to one of said radial extensions, whereby said vanes project outwardly from the hoops, and a vane controller, connected to a free edge of each of said vanes and to said rotor to limit the swinging motion of the vane in one direction only, whereby each of said vanes is free to align with the wind when on the side of the rotor which is advancing into the wind, but is restrained to a transverse position to the wind by said vane controllers when on the side of the rotor which is moving with the wind.

6. The structure set out in claim 5 further characterized in that the aforementioned vanes

are also adapted to be arranged in pairs and constructed of two similar vane-halves, one vane-half pivoted at its lower edge and located above its spoke and extension and the other vane-half pivoted at its upper edge and located below its 5 spoke and extension; a pulley fastened on said rotor; and flexible means passing through said pulley and fastened at its ends to said respective vane-halves adjacent the free ends thereof to thereby counterbalance the weight of one 10 vane-half by the weight of the other corresponding vane-half.

7. In a windmill of the character described, a vertical rotor, a building and a structure supporting said rotor, said structure consisting of two 15 three-based structural steel towers, triangular in cross section, vertical on the sides facing the rotor and slanting on the other sides, said towers being connected together near their upper ends with a bridge consisting of a system of cables and wires, 20 and extending above the connecting cables and wires, the middle of said system of cables and wires being slantingly braced to the tops of the tower-extensions and horizontally braced to the tower sides, protecting thereby the middle of said 25 cables supporting the upper end of the rotor-shaft against collapse and against vibrations.

8. In a windmill of the character described, including a vertical pivoted rotor, connectors positioned in said rotor and carrying a plurality of 30 eccentrically and vertically pivoted vanes and vane-controllers for controlling the positions of each of the vanes comprising linked elements, one of said linked elements being connected to the longer end of the vane and the other linked 35 element being pivotally mounted upon the connector of an adjacent vane, said last named linked element being heavier built, longer and telescopically connected to the first mentioned linked element and thereby preventing the corner 40 of the last named vane from coming in contact with the vane-controller, allowing thereby the vane a swing of 180 degrees of a circle and exposing the operative vane perpendicularly with the wind just at that time when the center of 45 the vane is swung farthest from the axis of the rotor.

9. In a windmill of the character described, including a vertically pivoted rotor, connectors positioned in said rotor and carrying a plurality of 50 eccentrically and vertically pivoted vanes and means for controlling the positions of each of said vanes comprising a headed plunger connected to the longer end of the vane, a frame slidably receiving the head of the plunger there- 55 in and pivoted to the connector associated with an adjacent vane at a point to one side of the frame, thereby allowing the vane a swing up to 180 degrees of a circle and exposing the operative vane perpendicularly with the wind just 60 at that time when the center of the vane is swung farthest from the axis of the rotor.

10. In a windmill of the character described, a plurality of vertically pivoted vanes of miniature size, a handle, a tubular element loosely mounted 65 on the top of said handle, a series of wires radiating from said tubular element and bent down to serve as axles for the vanes which are exposed to the wind coming from any direction, said vanes when they are running with the wind being 70 adapted to work with their entire surfaces from whichever side the wind comes.
